UNITED STATES PATENT OFFICE.

ERNEST J. ALLEN, OF ALBANY, NEW YORK, ASSIGNOR TO RATHBONE, SARD & COMPANY, OF ALBANY, NEW YORK, A CORPORATION.

GAS HEATER AND STOVE.

1,141,096.

Specification of Letters Patent.

Patented June 1, 1915.

Application filed April 25, 1914. Serial No. 834,474.

To all whom it may concern:

Be it known that I, ERNEST J. ALLEN, a subject of King George V of Great Britain, residing at the city of Albany, in the county 5 of Albany and State of New York, have invented certain new and useful Improvements in Gas Heaters and Stoves, of which the following is a specification.

My invention relates to gas heaters and 10 stoves, and the object of my invention is to provide a gas heater or stove so constructed that the burning gases will be controlled in order that the largest possible amount of the heat may be utilized; together with such 15 elements and combinations as are herein-after more particularly set forth and claimed. I accomplish these objects by means of the mechanism illustrated in the accompanying drawing, in which:

20 Figure 1 is a plan. Fig. 2 is a section along the lines, A—A on Fig. 1.

Similar letters refer to similar parts throughout the several views.

Within a suitable receptacle, A, I place 25 the fire brick, B, forming a hearth, through which are a series of gas inlets, C, for the admission of the gaseous mixtures. The hearth is preferably separated from the gaseous mixture chamber, D, by means of 30 suitable conduits, E, E, through which the gas inlets, C, are formed. I place a perforated plate, F, a short distance above the

mouth of the openings, C, in the fire brick, B. The gaseous mixture chamber, D, is connected to a gas-mixing apparatus, not 35 shown. The plate tends to confine the heat to the hearth. The gas passing from the gaseous mixture chamber, D, through the gas inlets, C, is lighted beneath the plate, F. The burnt gases escape through the perforations, H, in the plate, F.

As thus arranged and connected up the heat from the burning gases is intense within the hearth and by the plate, F, being perforated permits the products of combustion, 45 the latent gases, to pass out without forming beneath the plate where they would interfere with the conductivity of the heat in the burning gases.

What I claim as my invention and desire 50 to secure by Letters Patent is:

A hearth comprising a receptacle; fire brick placed therein; a series of conduits passing through said receptacle and said fire brick; a gas mixing chamber with which 55 said conduits register; and a perforated plate in said hearth above the openings of said conduits.

In testimony whereof I have affixed my signature in presence of two witnesses,

ERNEST J. ALLEN.
